UNITED STATES PATENT OFFICE.

JAMES M. GOSS, OF PEKIN, INDIANA.

CHURN.

SPECIFICATION forming part of Letters Patent No. 660,425, dated October 23, 1900.

Application filed February 3, 1900. Serial No. 3,817. (No model.)

To all whom it may concern:

Be it known that I, JAMES M. GOSS, a citizen of the United States, and a resident of Pekin, in the county of Washington and State of Indiana, have invented a new and Improved 5 Churn, of which the following is a full, clear, and exact description.

The purpose of the invention is to provide a simple and cleanly construction of upright 10 churn and a driving mechanism readily attachable to and detachable from the churn, which mechanism is of such a character that the body of the churn will be turned in one direction simultaneously with the dash being operated in a reverse direction.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both figures.

Figure 1 is a perspective view of the improved churn, and Fig. 2 is a vertical section through the churn and through the support therefor.

A base A supports a platform A', and this platform A' is adapted to support the churn 30 B, which is of the upright pattern. The base A is usually provided with legs 10 and the legs with casters 11. Uprights C extend from the rear portion of the base A, and between the upper portions of the uprights C a shaft 35 13 is mounted to turn. Preferably the shaft 13 is provided with recesses in its ends, which receive the conical extremities of bolts 14, which are adjustably placed in the uprights C, as shown in Fig. 1.

A driving mechanism C' for the churn is carried by the rock-shaft 13. This driving mechanism consists of a bracket 15, held in a horizontal position when connected with the churn by means of a set-screw 16, which 45 engages, preferably, with a wear-plate 17, secured upon a cross-bar 12, which extends from one upright C to the other below the rock-shaft 13. By means of the set-screw 16 the position of the bracket 15 relative to the 50 churn may be adjusted at any time. The bracket 15 extends over the upper portion of the churn to the center thereof, and a hori-

zontal shaft 18 is journaled in the bracket 15, one end of the shaft being provided with a crank 18*, while at the other or inner end of 55 the shaft a bevel-gear 19 is secured, and this bevel-gear is located between arms 20, which extend from the top and bottom of the bracket. A vertical shaft 21 is mounted to turn in the said arms 20 of the bracket 15, and this shaft 60 21 extends down a sufficient distance to enter an opening in the top 29 of the churn B. The lower end 23 of the shaft is polygonal in cross-section, as illustrated in Fig. 2. This shaft is revolved through the medium of a bevel-pinion 22, secured to the upper end of the 65 shaft and meshing with the teeth of the bevel-gear 19. An oppositely-disposed pinion 24 is mounted to turn upon the lower arm 20 of the bracket 15. This pinion likewise meshes 70 with the teeth of the bevel-gear 19, and a sleeve 25 is secured to the pinion 24, which sleeve 25 75 receives the shaft 21 and is carried longitudinally downward through the lower arm 20 of the bracket 15, as shown in Fig. 2. A clutch 26 is formed at the lower end of the sleeve 25, and the clutch 26 is adapted to engage with a mating clutch 27, formed upon a clamp 28, preferably of a spider pattern, which clamp is located on the cover 29 of the 80 churn. A second plate 30, preferably of similar construction to the upper plate 24, receives the bottom portion of the body of the churn B, and this lower plate 30 is provided at its center with a pin or a stud 31, which 85 enters and is mounted to turn loosely in a socket 32, formed in the upper end of a stud 33, which stud is capable of vertical movement in the central portion of the platform A' of the base of the frame. The stud 33 may 90 be raised through the medium of a lever 34, which is fulcrumed in an opening in the base, and its outer end may be depressed and held depressed through the medium of a cam-head 35, formed on a lever 36, the head of the lever 95 being pivoted in the opening which receives the lift-lever 34. When the cam-lever 36 is pressed downward at its outer end, the stud 33 is raised and the clutch 27 on the upper plate of the churn is brought into close engagement with the clutch 26 on the sleeve 100 connected with the lower bevel-pinion 24. The cover 29 of the churn is held in place preferably by forming hooks 37 at the ex-

tremities of the arms of the top and bottom plates 28 and 30, vertically-opposing hooks being connected by links 38, provided with turnbuckles or their equivalents.

5 The dash D is mounted to revolve within the body of the churn and may be of any suitable construction. In the drawings this dash consists of a central post 39 and wings 39^a, which radiate from the post, the wings being 10 slotted and apertured, and these wings act in conjunction with longitudinal ribs 39^b, secured to the side surface of the body of the churn B. The bottom of the central post 39 of the dash D is provided with a pointed pin 40, 15 which serves as a pivot and turns in a socket produced in an offset 41 from the inner central portion of the bottom of the churn, while the upper end of the center post 39 of the dash D has a polygonal recess made therein, 20 which receives the polygonal extremity 23 of the shaft 21.

In operation the driving mechanism C having been adjusted to the churn and the churn properly adjusted on the frame and lifted up, 25 so that the two clutches 26 and 27 connect, upon turning the crank-handle 18^a the shaft 21 and the sleeve 25 are revolved, one to the right and the other to the left, and under such an arrangement the body of the churn 30 is turned in one direction, while the dash D of the churn is simultaneously turned in a reverse direction. After the butter has come it may be gathered by turning the handle 18^a first to one side and then to the other.

35 When it is desired to gain access to the interior of the churn, the outer end of the lift-lever 34 is permitted to rise, whereupon the stud 33 will drop downward and the body of the churn will follow in the same direction, 40 thus separating the two clutches 26 and 27. The driving mechanism C may now be carried to the vertical position, (shown in dotted lines in Fig. 2,) and upon removing the turnbuckles from the links 38 the top of the churn 45 may be readily taken off, the butter removed, and the buttermilk poured off.

It will be observed that all the parts of the churn that come in contact with the milk are wood and that the churn is of such a simple construction that it may be thoroughly washed and its parts placed in the sun for purification.

Having thus described my invention, I claim as new and desire to secure by Letters Patent—

55

1. The combination with a vertically-movable support, a plate having a pin mounted to turn in said support, a churn the bottom of which bears on the said plate, the churn being provided with a cover and a revolving dash, an upper plate located on the cover and having a clutch projection; an adjustable connection between the top and bottom plates, and a driving mechanism adapted for connection with the dash and with the clutch projection on the said upper plate, substantially as described.

2. The combination with a vertically-movable support comprising a stud having a socket in its upper end, a lifting-lever fulcrumed between its ends and carrying said stud at one end, and a lever pivoted at one end and provided at said end with a cam-head adapted to engage the free end of the lifting-lever to actuate the same, of a churn, 75 a plate receiving the bottom portion of the churn and carrying at its bottom a pin adapted to turn in the socket in the upper end of said stud, a dash for said churn, a cover for said churn, a removable plate on said cover provided with a clutch, a connection between the top and bottom plates, and a driving mechanism for the churn and dash, the clutch on the said top plate being adapted to engage with a clutch carried by the driving mechanism when the churn is lifted, substantially as described.

3. The combination with a support, a churn, a plate on which the bottom of the churn bears, the said plate being mounted to turn on said support and provided with arms having hooks at their extremities, a cover for the churn, a plate located on the cover and having arms provided with hooks similar to those of the bottom plate, and an adjustable connection between the hooks of the top and bottom plates, substantially as described.

In testimony whereof I have signed my name to this specification in the presence of two subscribing witnesses.

JAMES M. GOSS.
